UNITED STATES PATENT OFFICE.

SAMUEL ROANE, OF MONTICELLO, ILLINOIS.

STORM-TOP FOR AUTOMOBILES.

1,366,280.

Specification of Letters Patent. Patented Jan. 18, 1921.

Application filed April 19, 1919. Serial No. 291,288.

To all whom it may concern:

Be it known that I, SAMUEL ROANE, a citizen of the United States, residing at Monticello, in the county of Piatt and State 5 of Illinois, have invented certain new and useful Improvements in Storm-Tops for Automobiles; and I do hereby declare the following to be a full, clear, and exact description of the invention, such as will enable others skilled in the art to which it 10 appertains to make and use the same, reference being had to the accompanying drawings, and to the letters and figures of reference marked thereon, which form a part of this specification.

This invention relates to new and useful improvements in storm tops for automobiles and consists of a simple and efficient device of this nature, so arranged that it may be 20 easily and quickly applied to the top, and affording means whereby the windows of the top may be opened or removed.

The invention comprises a simple and efficient device of this nature having other 25 various details of construction combination and arrangement of parts which will be hereinafter fully described, shown in the accompanying drawings and then specifically defined in the appended claim.

30 My invention is illustrated in the accompanying drawings which, with the letters of reference marked thereon, form a part of this application, and in which:

Figure 1 is a side elevation of an automobile showing the application of my storm 35 top thereto.

Fig. 2 is a horizontal sectional view taken on line 2—2 of Fig. 1, looking in the direction of the arrows;

40 Fig. 3 is a view in elevation showing a portion taken from the inside of the top.

Fig. 4 is a front elevation of the top.

Fig. 5 is a detail perspective view showing the relative movements of the hinged door and a hinged slide section in which a window is mounted, and

Fig. 6 is a sectional view on line 6—6 of Fig. 5.

Reference now being had to the details 50 of the drawings by numerals:

1 designates the usual top of an automobile and 2 the bows thereof. The storm top consists of a frame 3, the base portion thereof being provided with slots 4 forming 55 guide ways in which the windows 5 are adapted to slide. The upper portion of said

frame is also provided with similar slides for the reception of the windows. To permit the windows to be removed from the frame 3, a plate 6, shown in Fig. 3 of the drawings, and of a length substantially that of one of the windows 5, is mounted in a recess in said frame, said plate being adapted to have a limited vertical movement, guided by the pins 9, carried by the frame 65 3 and passing through slots 7 in the plate. Said plate, when in normal position to hold the window, has its upper and outer faces flush with the upper and outer faces of the frame 3.

The lower portion of the frame of the storm top has portions 11 which are hinged as at 12 to the bottom part of the frame, each portion 11 being positioned over and adapted to move with the usual hinged door 75 13 of the automobile body. Each hinged section 11 has a slot 14 therein, through which a bar or rod 15, secured to the door, passes, said bar tending to hold the part 11 upon the door as it swings upon its hinges. 80

It will be noted that when the door is swung open the part 11 will have a sliding movement independent of the door, for the reason that the part 11 and the door 13 have independent hinges. This sliding 85 movement of the part 11 and 13 is shown by dotted lines in the detail sections of the drawings. Hooks 17 are fastened upon the upper portion of the frame and are adapted to engage eyes upon the bows to further 90 assist in securely holding the top to the automobile.

At the forward end of the frame, a board 21 is fastened over the upper portion of the wind shield and serves to prevent rain or 95 snow from entering the space intervening between the upper window of the wind shield and the top of the frame when the window is lowered a short distance.

When the top is adjusted in place in the 100 manner shown and described, it will be noted that the windows may be opened by sliding the same back and forth in the guide ways, and in the event of it being desired to remove one or another of the 105 windows, it may be done by raising the plate upon the inside of the frame to permit the window to swing out of the guide ways. When it is desired to open the door of the car, the window is first slid along 110 through the guide ways free from the grooves or guide ways in the part 11 of

the frame, after which the door may swing with the hinged grooved part of the frame, the latter and the door having independent sliding movements.

5 By the provision of a storm top embodying the features of my invention, it will be noted that a simple and efficient means is provided which may be quickly and easily applied to the top of an automobile and 10 which will inclose the entire top making the car comfortable for riding in cold or stormy weather. The apparatus is so adjusted in place that it can be easily applied without marring the car, and quickly removed when desired.

15 What I claim to be new is:

A storm top for automobiles consisting of a frame having top and bottom channels

forming longitudinal guide-ways, windows 20 slidably mounted in said guide-ways, said frame having a recess of a length substantially that of one of said windows, pins carried by said frame at said recessed portion thereof, and a plate disposed in said recess and normally preventing removal of said 25 windows, and having slots through which said pins pass, whereby said plate has a limited vertical movement to permit removal of said windows.

In testimony whereof I hereunto affix my 30 signature in presence of two witnesses.

SAMUEL ROANE.

Witnesses:

RICHARD ROANE,
BLANCHE A. PERKINS.
